UNITED STATES PATENT OFFICE.

HENRY L. ZUCKER, OF MATAWAN, NEW JERSEY, ASSIGNOR TO A. P. MUNNING & CO.,
OF NEW YORK, N. Y., A CORPORATION OF NEW JERSEY.

BUFFING WHEEL.

Application filed September 26, 1921. Serial No. 503,464.

To all whom it may concern:

Be it known that I, HENRY L. ZUCKER, a citizen of the United States, residing at Matawan, in the county of Monmouth and 5 State of New Jersey, have invented a certain new and useful Buffing Wheel, of which the following is a specification.

The invention relates particularly to buffing or polishing wheels built up from pieces 10 of flexible fabric such as muslin, canvas, flannel or other material used for this purpose. Wheels of the above nature often are made of large diameter and are operated at high speed, with the result that the centrifugal force on the portions of the fabric 15 making up the buffing face is sufficient to stiffen and compact the cutting surface into a more dense and hard condition. But as the periphery of the wheel wears away with 20 continued use, the linear speed of the cutting surface becomes much less, such cutting surface is less stiffened or compacted, and the finish obtained by a small, worn wheel, may vary from that secured by a new, 25 full sized wheel of the same kind.

The invention has for an object to provide a buffing wheel of the above character in which, as the wheel periphery wears away, the quality or density of the buffing surface 30 nevertheless will remain substantially uniform.

Further objects and advantages of the invention will be in part obvious and in part 35 specifically pointed out in the description hereinafter contained, which, taken in connection with the accompanying drawings discloses a preferred embodiment thereof; such embodiment, however, is to be considered merely as illustrative of its principle. In the drawings:

Fig. 1 is a plan view of a buffing wheel made in accordance with the invention.

Fig. 2 is a cross sectional view of the wheel shown in Fig. 1.

45 The invention is disclosed as applied to a buffing wheel made up of pieces or laminations 1 of flexible fabric, which pieces in the present instance are in the form of complete circles, held or bound together in such manner that the binding means will wear away with the fabric until the major portion of the wheel has been consumed.

50 According to the present invention, the outer portions of fabric, or those portions 55 which travel at relatively high linear speed,

are held together less closely than the inner portions, thus making the buffing face of a full sized wheel of less natural density than that of the same wheel when worn smaller; therefore, as the wheel wears away in use, 60 the stiffening or compacting effect due to centrifugal force decreases, but the natural density of the cutting surface increases, and the resultant density of cutting surface may be maintained substantially constant for all 65 diameters.

In the illustrated form of the invention, the fabric pieces are bound together by means of stitching 2 which extends through the wheel from side to side, and which will 70 wear away together with the fabric as the wheel is used. The stitches are spaced apart further at the outer region of the wheel than at the inner region thereof, as may be accomplished conveniently by extending the 75 stitching spirally around the center of the wheel and spacing the turns of the spiral a greater distance apart as the diameter of the turns increases. Before the largest turn of the spiral has worn away, the edges 80 of the fabric which form the cutting surface of the wheel will be comparatively loose when the wheel is at rest, but when the wheel is turning at a high velocity the centrifugal force will tend to stiffen or straighten 85 out the fabric edges into a more compact and dense condition. As the wheel wears away the turns of the stitching are spaced apart less and less, and thus the average length of the cutting edges of the fabric 90 which project beyond the outermost turn of the stitching, becomes less, or, in other words, the edges of the fabric are held together more closely by the stitching, tending to make the cutting surface of the wheel 95 more dense. On the other hand, the linear velocity of the cutting surface is substantially smaller than at the periphery of the full-sized wheel, so that the stiffening effect of 100 centrifugal force is less. Thus by spacing the stitches distances approximately inversely proportional to their radial distances from the wheel center, the increase in density of the cutting surface due to the closeness of the stitching, may be made to compensate for the decreased density due to 105 reduction of the centrifugal force as the wheel wears away, and the density of the cutting surface may be maintained substantially constant.

The buffing wheel shown in Fig. 1 is designed to be discarded or put to different use after it has worn away to the point 3, and therefore the stitching inside of that point is not illustrated as spaced in accordance with the invention.

The spacing of the turns of the spiral stitching, as indicated on the drawing, is intended to show approximately proportions satisfactory for a wheel of 16 inches diameter adapted to be worn away to a diameter of 7 inches on the same class of work.

While a specific embodiment of the invention has been described, it is obvious that many changes may be made therein without departing from the spirit of the invention as defined in the following claims.

I claim:

1. A buffing wheel made up of fabric pieces, and means for binding the pieces together more closely at the inner region of the wheel than at the outer region thereof.
2. A buffing wheel made up of fabric pieces, and means for binding the pieces together at different portions of the wheel to an extent substantially inversely proportional to the radial distances of such portions from the wheel centre.

3. A buffing wheel made up of fabric pieces, and stitches for binding the pieces together, adjacent stitches at the outer region of the wheel being radially spaced apart a distance greater than the stitches of the inner portion of the wheel.

4. A buffing wheel made up of fabric pieces, and stitches for binding the pieces together, the stitches at different portions of the wheel being spaced apart radially, distances substantially inversely proportional to the radial distances of such portion from the wheel centre.

5. A buffing wheel made up of fabric pieces, and means for binding the pieces together comprising stitching extending spirally about the centre of the wheel, the turns of the spiral being spaced apart distances increasing toward the periphery of the wheel.

In testimony that I claim the foregoing, I have hereunto set my hand this 13th day of June, 1921.

HENRY L. ZUCKER.
